MACHINE FOR LOADING RUBBER-HEEL BLANKS WITH WASHERS.

Application filed May 8, 1923. Serial No. 637,526.

This invention relates to a machine for loading rubber heel blanks with washers.

A rubber heel of the common commercial form has a number of washers embedded in the body thereof, these washers being designed to support the heads of the nails, screws, or other fastenings by means of which the heel is secured to a shoe and to distribute the strain exerted by these fastenings over a greater part of the body of the heel than otherwise would be the case.

The usual process of manufacturing rubber heels consists in making an unvulcanized rubber heel stock of suitable composition, working this stock into sheets of appropriate thickness, cutting out heel-shaped blanks from this stock, and then molding and vulcanizing these blanks to form finished heels. The embedding of the nail receiving washers in the heels is, according to the present practice, performed incidentally to or as a part of the molding operation. That is, the washers are placed on posts located in the heel cavities of the molds, and a blank is then placed on these posts and is pressed into the cavity by the upper mold plate, thus forcing the washers into the body of the blank. The posts hold these washers in the proper relationship to the body of the heel during the molding and vulcanizing operations. The placing of the washers on the studs or posts in the mold cavities thus is a part of the duty of the press operator or molder. According to the present practice the production from a given press is limited by the length of time required for the molder to place washers on the posts in the molds. The molder is handicapped in performing this part of his duties by the fact that the molds are hot, and also by the fact that the posts are necessarily so located with reference to the other parts of the mold that the molder is hampered in placing the washers on the posts.

The present invention deals with the problem presented by these conditions, and it has for its chief object to devise a machine for automatically loading rubber heel blanks with washers. The invention proposes to relieve the molder entirely of the duty of

handling washers, each heel blank being loaded with washers when it comes to the molder so that it will be simply necessary for him to place one blank in each mold cavity, the washers carried by the blank being so spaced that they will register with the washer pins in the molds. Economies thus are effected both in the molding operation and also in the placing of the washers in the heels.

The invention aims to devise a machine which will embed the entire set of washers in one operation in the heel blank in substantially the positional relationship which they are to bear to each other in the finished heel.

The nature of the invention will be readily understood from the following description when read in connection with the accompanying drawings, and the novel features will be particularly pointed out in the appended claims.

In the drawings:—

Figure 1 is a front elevation of a machine embodying the present invention, the heel blank magazine, however, being omitted;

Fig. 2 is a side elevation of the machine shown in Fig. 1 but including the magazine;

Fig. 3 is a plan view of the heel blank feed plate and adjacent parts;

Fig. 4 is a plan view of a rubber heel blank showing the washer locations and showing one washer embedded therein by the machine shown;

Fig. 5 is an enlarged cross sectional view on the line 5—5, Fig. 4;

Fig. 6 is a vertical cross sectional view through the die blocks and plunger mechanism of the machine shown in Figs. 1 and 2;

Fig. 7 is a horizontal cross sectional plan view showing the driving mechanism for the heel blank feeder;

Fig. 8 is a vertical cross sectional view through a part of the plunger and die mechanism;

Fig. 9 is a cross sectional view on the line 9—9, Fig. 14;

Fig. 10 is an elevation showing a detail of the washer feeding mechanism;

Fig. 11 is a horizontal cross sectional view through the cross head of the machine;

Fig. 12 is a bottom view of the body of the upper die and adjacent parts with the filler blocks removed, the ends of the washer chutes and the plates in which they are supported being shown in horizontal cross section;

Fig. 13 is a cross section of one of the washer hoppers, the parts contained therein being shown in plan;

10 Fig. 14 is a cross sectional view on the line 14—14, Fig. 13;

Fig. 15 is an enlarged view of a part of Fig. 13;

15 Fig. 16 is a view similar to Fig. 15 but showing the parts at a subsequent point in the washer feeding operation;

Fig. 17 is a cross sectional view on the line 17—17, Fig. 15; and

20 Fig. 18 is a cross sectional view on the line 18—18, Fig. 15.

The machine illustrated in the drawings comprises, briefly stated, a loading mechanism including upper and lower dies with a series of plungers guided in the upper die 25 and operative to force a set of washers simultaneously into a heel blank supported on the lower die; a blank feeding mechanism which presents the heel blanks one at a time to the loading mechanism, and washer feeding mechanism which delivers washers to the loading mechanism in position to be forced into the heel blanks.

Referring first to Figs. 1, 2 and 6, the upper die block is indicated at 2, and the 35 lower die at 3. The lower die consists of a plate having a series of apertures 4 therethrough arranged in substantially the positional relationship to each other which it is desired to have the washers bear to each other in the heel blank, this die being removably mounted in a table or bed 9. The 40 upper die block comprises a main body or block 5 with a face plate 6 secured to its lower side, these members having holes therethrough to receive plungers 7 arranged in alinement with the holes 4 in the lower die plate. These plungers also project through holes in a plate 8, Fig. 6, which is held in spaced relationship to the block 5 by means of four posts 103, Figs. 1 and 12, and the plungers are secured at their upper ends in a plunger head 10. This head is slotted to receive the head 12 of a large screw 13 which is threaded into a cavity 55 formed in the lower side of a cross head 14. The cross head is mounted to reciprocate in vertical guide bars 15—15, Fig. 11, which are bolted to the machine frame 16. A crank arm 17, Fig. 1, has a rounded head 18 at its lower end which is mounted in a similarly shaped socket formed in the cross head 14, and the upper end of the crank arm is mounted on a pin 19 which projects eccentrically from a disk 20 secured to the forward end of the main shaft 21. At its rear-

ward end this shaft carries a pulley 22 by means of which the machine may be belted to any convenient source of power.

It will now be evident that when the machine is in operation the plungers 7 are reciprocated toward and from the lower die block 3.

The blank feeding mechanism presents the rubber heel blanks one at a time between the dies 2 and 3, and the plungers force the 75 washers flatwise into the body of the blank. This feeding operation is performed by a rotary feed plate 24, best shown in Fig. 3, this plate being provided with a series of heel-shaped apertures 25 each adapted to receive a heel blank. The feeder takes the blanks from the bottom of a magazine, indicated in general at 26, Figs. 2 and 3, which is adapted to support a vertical stack of rubber heel blanks, the lowermost blank in the 80 stack resting on the surface of the feeder 24. The magazine comprises a bracket 27 which is bolted to the side of the bed or table 9 so that it can be adjusted vertically, this bracket having a horizontal portion that 85 overlies a part of the feeder 24. Bolted to the horizontal portion of this bracket is an upright V-shaped plate 28 designed to support the rounded ends of the heel blanks, and two vertical pieces 29 and 30 of angular 90 cross section designed to support the opposite sides and breast corners of the blanks, as clearly shown in Fig. 3. All of these parts are adjustably secured to the bracket 27 so that the dimensions of the magazine 100 can be varied to accommodate a variety of sizes of blanks. The feeder is rotated intermittently, and as the apertures 25 come in line with the stack the lowermost heel blank therein drops into one of the apertures, and upon the next forward movement of the feeder, this blank is carried out of the stack and is moved forward over the surface of the table or bed 9.

For the purpose of giving the feeder 24 110 its intermittent movement it is secured on the upper end of a shaft 31, Figs. 2 and 7, which is supported partly in the table 9 and partly in a spider or plate 32 which is bolted to said table. A Geneva wheel 33 is secured fast to the shaft 31 and cooperates with a Geneva driver consisting of a disk 34 and a roll 35, Figs. 2 and 7. This driver is secured to a gear 36 which meshes with a gear 37 pinned to the lower end of a vertical 120 shaft 38. The upper end of this shaft is connected through mitre gears 40, Fig. 2, with the main shaft 21 previously referred to. This driving mechanism thus operates to rotate the feed plate 24 step by step, each 125 feeding movement carrying the plate through an angle of 90°.

Referring to Fig. 3, it will be observed that the feeder 24 receives a blank from the magazine 26 in the position B¹. It next ad- 130

vances this blank to the idle position B², and upon the next succeeding feeding movement, it carries this blank to the position B where it is located between the upper and lower dies in readiness to be loaded with washers.

The next feeding movement of the plate carries this loaded blank over an aperture 42 in the table 9, and the heel drops through this aperture into a suitable receptacle.

10 The feed plate 24 rotates in a clockwise direction, as it appears in Fig. 3, and the blank receiving apertures 25 are arranged with their rounded ends foremost so that as the blanks are advanced toward the dies they 15 are thrown outwardly by centrifugal force against the outer edges of the apertures. They are moved forward by the contact of the edge of the aperture with the breast edge of the blank, so that each blank, when 20 finally presented to the loading mechanism, is located in the outer left-hand corner, Fig. 3, of the blank aperture. The position of the blank B in Fig. 3 clearly illustrates this point. The feeder thus not only performs 25 the function of feeding, but also of positioning, or gaging the position of, the blanks for the loading operation.

In order to still further ensure the correct 30 positioning of the blanks, a plunger is arranged to move partly through the lower die block 3 to press the blank against the upper die block. This plunger comprises a head 43, Figs. 3 and 6, on the upper end of a stem 44 which is guided in the hollow stud 35 45. A spring 46 tends to force the plunger upwardly and the movement of the plunger so produced is limited by a nut 47 screwed on the lower end of the stem 44. As the feed plate 24 swings the blank into position 40 between the dies, the drag of the plunger head 43 on the blank assists centrifugal force in moving the blank into the outer left-hand or "trailing" corner of the aperture 25 in which the blank is located. The plunger 45 also presses the blank against the lower face of the upper die block and prevents any rebounding of the blank when the feed plate stops.

While the blank is held in this position 50 the entire series of washers which are to be embedded in it are dropped upon the upper surface of the heel. The washer feeding mechanism consists of two sections or feeding mechanisms which are duplicates of each 55 other, as best shown in Fig. 1, and comprises hoppers 50 and 51 mounted at opposite sides of the machine, and connected through washer delivery tubes or chutes 52 and 53 to the opposite sides of the upper die block 60 2. It will be seen from an inspection of Figs. 3 and 4 that the heel blank B is designed to have eight washers inserted therein. Consequently, the washer delivering mechanism shown is arranged to deliver 65 four washers from each hopper simultane-

ously to the die block. Inasmuch as the washer feeding mechanisms are duplicates of each other, the mechanism located at the right of the machine only will be described in detail.

Referring to Figs. 1, and 13 to 18 inclusive, it will be seen that the hopper 50 is supported in a stationary position on a bracket 54. This hopper is adapted to contain a mass of washers which are simply dumped into it without regard to arrangement. The hopper is inclined at an angle of about 45°, as best shown in Fig. 2, so that the washers will normally rest in the lower part of the hopper. Mounted closely against the bottom 55 of the hopper is a selector plate 56 having a series of radial slots 57 formed in its edge, these slots being of a width to receive the washers W. The margin of the selector plate 56 is of about the thickness of a washer, while the central portion thereof is of more substantial dimensions, and this plate is secured fast on the end of an inclined shaft 60.

As the selector plate 56 rotates slowly through the tumbled mass of washers, the slots 57 will be more or less completely filled by washers arranged edge to edge, as shown in Fig. 13, the slots being long enough to hold four washers. As the slots swing upwardly, the washers drop by gravity toward the inner ends of the slots, and they finally come to a position, as shown at the right of Figs. 3 and 15, over apertures 62 which are formed through the bottom plate 55 of the hopper and constitute the mouths of the washer chutes or tubes 52. These openings or mouths 62, however, are closed at this time by a shutter or plate 63 which sets into the plate 55 flush therewith, and on which the washers are supported at this time. This shutter has a shank 64, and both the shutter and its shank are located in a recess formed in the plate 55, as best shown in Fig. 14. The shutter normally is held in its closed position by means of a spring 65.

It will be observed that the slots 57 are arranged in groups of four, and that they are so spaced that the innermost washer in all four slots of any group will register with the mouths 62 simultaneously. When the parts reach this relationship, the shutter is drawn backwardly far enough to uncover the openings 62, thus causing the washers resting on the shutter to drop into the chutes 52.

For the purpose of moving the shutter backwardly to open it at the desired points in the rotation of the selector plate 56, a cam plate 66 is secured to the shank 64 by means of a screw 67. The selector plate 56 carries a series of studs or rolls 68, one for each group of slots 57, and these studs or rolls are arranged to engage the inclined face of the cam 66 and force this cam back-

wardly, as best shown in Fig. 16. The shutter 63 moves with the cam 66 and consequently is opened by the travel of each roll 68 past the cam. As soon as the roll leaves the cam the spring 65 immediately closes the shutter again.

In order to prevent more than one washer being discharged into each washer tube at a time, a guard plate 70 is mounted in the 10 hopper on posts 71-71 in a position parallel to the wall of the hopper and with its lower edge extending down to the selector plate 56. The upper end of the guard 70 is curved inwardly slightly, as indicated at 15 72, Figs. 13 and 15, so that as the washers are carried past this guard by the selector plate, the innermost washer in each slot 57 will pass on the inner side of the guard, while all the other washers will be compelled to 20 pass on the outer side thereof. When the shutter is opened only those washers on the inner side of the guard can drop into the mouths of the chutes.

Two kinds of washers are commonly used 25 in rubber heels, namely, a flat washer and a dished or concaved washer. When the latter kind is used, it is important that the washers be presented to the loading mechanism with their concaved sides all facing in one direction; in this instance with their concaved faces up. The selector plate of the mechanism above described is so thin in the neighborhood of the slots 57 that it will only 30 carry a concaved washer in its inverted position, as shown at W', Fig. 10, but it will reject or fail to convey a washer with its concaved side uppermost, as indicated at 35 W'', Fig. 10. All the washers brought around to the shutter 63, therefore, are in their inverted positions, as shown in Fig. 17. This shutter is slowly drawn backwardly in the manner above described, so that support for each washer is first withdrawn from 40 under the outer edge of the washer W. It will therefore tip downwardly into the chute 45 52 with its concave side inwardly toward the center of the machine. It will be understood that the washer is moved forward continuously while the shutter is opening, but that 50 the long slot which forms the mouth of the chute affords ample time for the washer to drop into it, this construction giving the effect of a "dwell" in the movement of the selector plate. It should also be noted that 55 there is a slight clearance between the outer edge of the slot 62 and the outer edge of the shutter when the shutter is in its closed position. This is clearly shown in Figs. 15 and 17, and this arrangement produces the advantage of preventing the shutter from closing 60 on a washer which is just toppling into the mouth of the chute and preventing the complete discharge of the washer. The chutes or tubes 52 are made of rectangular 65 cross section and so thin that it is impossible

for the washer to turn over after it has entered the tube, but the tubes are so curved that they turn the washers right side up before they deliver them to the loading mechanism.

Flat washers do not present the same difficulty encountered in handling concave washers but both can be handled with equal facility by the mechanism above described.

Different styles and sizes of heels require 75 different numbers of washers. A number greater than eight is rarely required, but in such cases the selector plate is provided with additional slots 57 and one or more additional washer chutes are provided, the shutter being correspondingly widened to control the additional chute or chutes. These changes in design will be obvious. When a smaller number than four is to be delivered by one feeding mechanism, the position of the cam 66 is changed to advance the opening of the shutter and thus to prevent the discharge 80 of washers into one or more of the chutes.

Referring to Figs. 9 and 15, it will be observed that the shank 64 is provided with 90 two sockets 74 and 75 to receive the head of the screw 67 in addition to the socket in which this screw is located in these figures. If the cam 66 is moved backwardly (with 95 reference to the direction of rotation of the selector plate) and clamped by the screw 67 with the head located in the socket 75, the shutter then will be opened when the foremost slot 57 in each group reaches the third chute mouth 62. Consequently, the fourth chute, which in this instance is the lowermost chute in Fig. 15, will not receive a washer. Three washers only will be delivered, therefore, at each opening of the shutter. If the cam 66 is moved back one 100 more notch, with its screw 67 located in the socket 74, the two rearmost chutes only will receive washers, as will readily be appreciated. This simple adjustment, therefore, 105 enables the operator to vary the number of washers delivered at will within the limits for which the machine is designed.

The shafts 60-60 of the two washer feeding mechanisms have mitre gear connections with a horizontal shaft 80, Figs. 1 and 2, 110 which is driven through a bevel gear connection 81 with the vertical shaft 38 previously referred to.

The lower ends of the washer tubes 52 and 120 53 are secured, respectively, in the fixed plates 78 and 79, Fig. 6, at the opposite sides of the upper die block. These tubes open directly into washer passages 84 formed in the opposite sides of the member 5 of the upper die block, and these passages lead 125 to the respective holes in which the plungers 7 are mounted, as best shown in Figs. 6 and 12. The passages 84 preferably are made by milling slots in the opposite sides of the block 5, and then partially filling these slots 130

with filler blocks 86, Fig. 6, which are held in place by screws 87, and are of such dimensions that they form passages which constitute the lower ends of the washer chutes 5 and are of substantially the same dimensions as the passages in the tubes 52 and 53. It will be seen that these passages are inclined downwardly at a sharp angle and that they are so narrow as to prevent the washers from 10 turning over.

When the washers reach the discharge ends of their chutes, they are stopped by gates or valves 88 consisting of sleeves that encircle the plungers 7. The upper ends of 15 these sleeves are secured in a sleeve head or plate 90 having slots 91-91, Fig. 11, at its opposite sides to receive two rods 92-92 that project into holes formed in the cross head 14. These rods have heads or enlargements 20 93 and 94 at their upper and lower ends, respectively, and they extend through bushings 95-95 threaded in the cross head. A lost motion connection thus is provided between the cross head and the sleeves or 25 gates 88.

The arrangement preferably is such that the sleeves are held at the lowermost limit of their range of movement while the cross head lifts the plungers 7, but just before the 30 cross head reaches the upper limit of its stroke, the heads 93-93 strike the bushings 95-95 and lift the rods 92-92, raising the sleeves or gates 88 with them far enough to release the washers W and allow them to 35 drop into the plunger holes in the upper die block. The position of one of the gates at this time is shown in Fig. 8. As soon as a washer is so released, it slides into the plunger passage and drops on to the upper 40 surface of the blank B, as clearly shown in Fig. 8, this movement of the washer being facilitated by the sharp inclination of the washer chute at its delivery end. When the cross head 14 starts on its downward stroke, 45 the gates or valves 88 move downwardly with it until they are returned again to their original or seated positions where they close the discharge ends of the washer chutes. This closing movement of the gates or 50 valves is effected partly by gravity and partly by a spring 97, Fig. 6, which bears at its lower end on the head 98 of a rod 99, the upper end of this rod being threaded into the sleeve plate 90. The upper end of the 55 spring 97 bears on the plate 8, and consequently, this spring tends to hold the plate 90 and the sleeves 88, secured thereto, in their lowermost positions.

It may here be mentioned that the fact 60 that the gates or valves 88 are opened only for a very brief instant during each cycle of operations of the machine, is an important advantage since it affords the washer selecting mechanism ample time to pick up washers from the hoppers and deliver them to the

die block in readiness to drop into the plunger passages as soon as the gates are lifted. The stopping of the washers at or near the discharge ends of their chutes and in such a position that they have only a short distance 70 to fall before striking the heel blank is of advantage in controlling the washers and preventing them from turning over or standing up on edge.

It will now be appreciated that when the 75 machine is in operation, it is simply necessary for the attendant to keep the magazine 26 supplied with blanks and the hoppers 50 and 51 supplied with washers. As the feeder 24 rotates intermittently, the bottommost 80 blank in the magazine 26 drops into one of the apertures 25 and it is carried forward to a point between the upper and lower dies, it being properly positioned by the feeder and by the plunger 43. The plunger presses 85 the blank against the lower face of the upper die. In the meantime the washer feeding mechanism has delivered eight washers to the discharge ends of the washer chutes and these washers are resting against the sides of 90 the gates or sleeves 88. Immediately after the blank has been positioned between the dies, the sleeves 88 are lifted and the washers immediately drop into the plunger passages and come to rest on the upper surface 95 of the blank. An instant later the sleeves 88 are lowered into their closed positions, and the plungers 7 descend and force all the washers simultaneously into the body of the heel blank. When the feeder 25 moves another step to present another blank to the dies simultaneously discharges the loaded blank through the aperture 42 in the table 100 9.

It should be noted that the outer surfaces 105 of the plungers near their lower ends are grooved longitudinally as best shown in Figs. 6 and 8. This arrangement is of advantage in allowing the material of the heel blank to squeeze inwardly above the washer as the washer is forced into the heel and thus to retain the washer in its embedded position during and after the withdrawal of the plunger. The tips on the lower ends of the plunger center the washers on them 110 during the embedding operation. Figs. 4 and 5 illustrate very well the appearance which a washer and the adjacent parts of the heel blank present after the embedding operation has been completed.

The stock or composition of which a heel blank usually is made is very elastic, and it therefore presents peculiar difficulties to the embedding of the washers in the manner 115 above described. Since this stock is usually very resilient, it tends to squeeze the washers out as the plungers are withdrawn. The stock also tends simply to compress under the washer and to return to its original condition as soon as the plunger is withdrawn. 120 125 130

These difficulties in some measure are overcome by the use of a grooved plunger, as above described. We have also found that the use of a lower die plate having apertures, such as those indicated at 4, Figs. 3, 5 6 and 8, in line with the plungers is very important in facilitating the embedding of the washers properly in the blank, particularly when the machine is running at reasonably high speeds. The stock in the blank 10 immediately under any individual washer is depressed into the aperture 4, and apparently a part of the material of the heel is sheared by the entrance of the washer. In 15 any event, it has been definitely ascertained that this construction enables the machine to operate at a much higher speed than otherwise would be possible.

The depth to which the washers must be 20 forced by the plungers varies with different compositions of stock in the heel blank. In some cases it is necessary to have the lower face of the plunger travel into the aperture 4 and actually go below the upper surface of 25 the die 3 in order properly to embed a washer in the blank. The stroke of the plungers, therefore, is made adjustable; that is, the minimum distance between the lower limit of movement of the end of each plunger 30 and the surface of the lower die 3 may be varied by adjusting the screw 13 in the cross head 14, the length of stroke of the plunger remaining constant.

The simultaneous embedding of the entire 35 set of washers in the blank results in expanding the blank slightly, and this fact is taken into consideration in arranging or spacing the plungers. That is, the plungers 40 7 do not have exactly the positional relationship to each other that the mold pins bear to each other, but do have substantially such a relationship, the plungers being set inwardly toward each other slightly by, perhaps, one-sixteenth of an inch in an average size man's 45 heel. That is not always necessary, particularly if the washers are grouped closely, but it is preferable in large heels in order to 50 compensate for the expansion of the heel produced by the washer embedding operation, and it results in so spacing the washers in the blank that they will register properly with the mold pins.

Different sizes and styles of heels have a 55 different number and arrangement of washers. The plungers 7 in the upper die and the holes 4 in the lower die correspond substantially in number and arrangement to the 60 number and arrangement of the washers in the finished heel. Consequently, it is necessary to use different dies for different heels. The present machine, therefore, includes 65 provision for readily changing the dies.

The lower die is supported in a slot formed in the bed 9, as best shown in Figs. 2

and 3. It is held against lateral displacement by suitable dowel pins (not shown) and by the central plunger 43.

The upper die, with the plungers 7 and sleeves 88, is arranged to be removed by a movement forward out of the machine. The 70 opposite edges of the plate 8 are mounted in guideways formed in the machine frame between upper plates 100—100 and lower plates 101—101, as clearly shown in Figs. 1 and 6, and it is held in its operative position in the 75 machine by a latch pin 102, Figs. 6 and 12. This plate and the die block 5 are rigidly secured together in spaced relationship by four posts 103, Figs. 1 and 12. When the pin 102 is removed, the entire upper die with 80 the plungers and sleeves and the plunger head 10 and sleeve plate 90 can be slipped forward out of the machine. It will be evident from an inspection of Figs. 6 and 11 85 that the slots 91—91, Fig. 11, allow the plate 90 to slide forward out of engagement with the rods 92—92, while the open ended slot 104, Fig. 11, in the plunger head 10 allows this part to slip laterally off the head 12 of the screw 13. Another upper die of the same 90 general construction as that shown, but having a different arrangement of plungers, may then be slipped into the machine in the reverse direction; a suitable lower die also 95 being placed in the bed 9 to cooperate with the new upper die.

It will be understood that the washer passages 84 in the blocks 5 of all the upper dies are arranged to register with the washer tubes or chutes 52 and 53 when the die is in 100 its operative position. These washer tubes, therefore, remain fixed in the machine and are not disturbed by the substitution of one die for another.

The machine above described is designed 105 to embed the washers in the body of the heel blank. It is contemplated, however, that this may not be necessary or desirable in all cases and that the washers may be anchored in or secured to the blank in some other 110 manner. For instance, it is contemplated that the washers may be provided with prongs which will be embedded in the heel blank, the main body of each washer resting 115 on the surface of the blank. Other expedients also may be adopted for holding the washers in their proper positions on the heel blank.

The holes 4 in the lower die plate appear 120 to be of advantage not only for the reasons above described, but also in that the movement of the part of the stock of the heel blank into these holes or apertures appears to have the effect of pulling the stock in the upper parts of the blank inwardly around 125 the plungers where the stock tends to close the holes made by the plungers, and consequently acts to hold the washers securely in

their embedded positions after the plungers have been withdrawn. This construction also appears to reduce the resistance to the embedding of the washers in the stock, the stock being depressed more readily than when it is forced horizontally, as would be the case with a flat imperforate die plate. The presence of this lower aperture also is of advantage in facilitating the shearing action which has been mentioned that apparently takes place when the washer is forced into the stock.

It will be appreciated that while we have herein shown and described the best embodiment of our invention which we have so far devised, the invention is susceptible of embodiment in many forms without departing from the spirit or scope thereof. So far as we are aware no machine has been devised heretofore for loading a rubber heel blank with washers, and we desire, therefore, to claim our invention broadly.

The washer sorting mechanism is not claimed in this application but is claimed in our divisional application Serial No. 64,542, filed October 24, 1925.

Having thus described our invention, what we desire to claim as new is:—

1. A machine for loading rubber heel blanks with washers comprising, in combination, positioning means for a rubber heel blank, a plunger, mechanism for reciprocating said plunger toward and from a heel positioned by said means, and means for automatically presenting washers one at a time between said blank and plunger and in position to be forced into said blank by said plunger.

2. A machine for loading rubber heel blanks with washers comprising, in combination, a plunger for forcing a washer into a blank, a support for said blank, said support having an aperture therein to receive a part of the material of said blank displaced by said plunger as the plunger forces the washer into the heel, and means for giving said plunger its operative movement.

3. A machine for loading rubber heel blanks with washers comprising, in combination, a plunger for forcing a washer into a blank, a support for said blank, said support having an aperture therein to receive a part of the material of said blank displaced by said plunger as the plunger forces the washer into the heel, means for automatically presenting washers one at a time in position to be forced into said blank by said plunger, and means for giving said plunger its operative movement.

4. A machine for loading rubber heel blanks with washers comprising, in combination, a plunger for forcing a washer into a blank, a support for said blank, means for automatically depositing a washer on the

surface of said blank in position to be forced into the blank by said plunger, and means for operating said plunger to cause it to embed said washer in the blank.

5. A machine of the character described comprising, in combination, means for embedding a plurality of washers simultaneously in a rubber heel blank, a magazine for holding a supply of heel blanks, and blank feeding mechanism operative to take blanks one at a time from said magazine and present them to said means.

6. A machine of the character described comprising, in combination, mechanism for loading a rubber heel blank with washers, means for feeding blanks to said mechanism comprising a plate with a blank aperture therein, and means for moving said plate to present a blank positioned in said aperture to said loading mechanism.

7. A machine of the character described comprising, in combination, mechanism for loading a rubber heel blank with washers, and a rotary feeder for presenting blanks to said mechanism.

8. A machine of the character described comprising, in combination, mechanism for loading a rubber heel blank with washers, and a rotary feeder operative to present blanks to said loading mechanism and to discharge the loaded blanks from the machine.

9. A machine of the character described comprising, in combination, mechanism for loading a rubber heel blank with washers, blank feeding means comprising a rotary plate having a plurality of blank receiving apertures therein, and a Geneva mechanism for rotating said plate step by step to deliver blanks to said loading mechanism.

10. A machine of the character described comprising, in combination, mechanism for loading a rubber heel blank with washers, a rotary plate having a plurality of blank receiving apertures therein, a magazine for holding a stack of blanks in position to have the lowermost blank drop into an aperture in said plate as said apertures are brought successively into register with the stack, a table over the surface of which the blanks are moved by said plate, and mechanism for rotating said plate step by step to cause it to deliver blanks from said magazine to said loading mechanism.

11. A machine of the character described comprising, in combination, mechanism for loading a rubber heel blank with washers, a blank feeding mechanism operative to deliver blanks one at a time to said loading mechanism, said feeding mechanism comprising a rotary plate having a plurality of apertures therein, each aperture being adapted to receive a plurality of sizes of blanks, and means for acting on each blank to hold

it in a predetermined portion of the aperture when the blank is presented to said loading mechanism.

12. A machine of the character described comprising, in combination, mechanism for loading a rubber heel blank with washers, said mechanism including a die block, blank feeding mechanism operative to deliver rubber heel blanks one at a time to said die block, and a spring pressed plunger for pressing each blank so presented against the face of the die block.

13. A machine of the character described comprising, in combination, mechanism for loading a rubber heel blank with washers, said mechanism comprising upper and lower dies, a blank feeding mechanism operative to feed blanks one at a time into a position between said dies, and a spring pressed plunger in the lower die operative to press each blank so fed against the lower face of the upper die.

14. A machine for loading rubber heel blanks with washers comprising, in combination, a plunger for forcing a washer into a blank, and a support for said blank, the outer surface of said plunger having longitudinal grooves therein.

15. A machine for loading rubber heel blanks with washers comprising, in combination, a plunger for forcing a washer flatwise into a blank, and a support for said blank, said plunger being constructed to permit the material of the heel blank to squeeze inwardly around the edge of the washer after it has been embedded in the blank to hold the washer in the blank during and after the withdrawal of the plunger.

16. In a machine for loading rubber heel blanks with washers, the combination of a plunger for embedding a washer in a rubber heel blank, a support for said blank, a die block in which said plunger is mounted to reciprocate, and a washer chute leading laterally into the hole in said block in which the plunger reciprocates.

17. In a machine for loading rubber heel blanks with washers, the combination of a plunger for embedding a washer in a rubber heel blank, a support for said blank, a die block in which said plunger is mounted to reciprocate, a washer chute leading laterally into the plunger passage, and a gate at the discharge end of said chute controlling the movement of the washers into the plunger passage.

18. In a machine for loading rubber heel blanks with washers, the combination of a plunger for embedding a washer in a rubber heel blank, a support for said blank, a die block in which said plunger is mounted to reciprocate, a chute leading laterally into the plunger passage in said block, a sleeve encircling said plunger and operative to control the discharge of washers from said

chute into said passage, and actuating means for said plunger and sleeve.

19. In a machine for embedding washers in rubber heel blanks, the combination of a die block having a number of holes therein corresponding in number and arrangement to the number and arrangement of the washers to be embedded in each blank, plungers movable in said holes for forcing the washers simultaneously into the blanks, and washer chutes leading into said holes.

20. In a machine for embedding washers in rubber heel blanks, the combination of a die block having a number of holes therein corresponding in number and arrangement to the number and arrangement of the washers to be embedded in each blank, plungers movable in said holes for forcing the washers simultaneously into a blank, washer feeding mechanism operative automatically to deliver a washer to each plunger, and means for supporting a rubber heel blank in position for the operation thereon of said plungers.

21. In a machine for embedding washers in rubber heel blanks, the combination of a die block having a number of holes therein corresponding in number and arrangement to the number and arrangement of the washers to be embedded in each blank, plungers movable in said holes for forcing the washers simultaneously into the blanks, a washer chute leading laterally into each of said holes, a gate located substantially at the discharge end of each chute and controlling the delivery of washers into said holes, mechanism for operating said gates in unison, and operating means for said plungers.

22. In a machine for embedding washers in rubber heel blanks, the combination of a die block having a number of holes therein corresponding in number and arrangement to the number and arrangement of the washers to be embedded in each blank, plungers movable in said holes for forcing the washers simultaneously into the blanks, a washer chute leading laterally into each of said holes, a sleeve encircling each plunger and normally operative to prevent the discharge of washers from said chutes into said holes, and operating mechanism for said plungers and sleeves.

23. In a machine for embedding washers in rubber heel blanks, the combination of a die block having a number of holes therein corresponding in number and arrangement to the number and arrangement of the washers to be embedded in each blank, plungers movable in said holes for forcing the washers simultaneously into the blanks, mechanism for delivering washers into said holes, operating mechanism for said plungers, and means for supporting said die block for removal from said operating and washer feed.

ing mechanisms, whereby it may be replaced at will by another die block.

24. In a machine for embedding washers in rubber heel blanks, the combination of a die block having a number of holes therein corresponding in number and arrangement to the number and arrangement of the washers to be embedded in each blank, plungers movable in said holes for forcing the washers simultaneously into the blanks, washer passages in said block leading into said holes, means removably supporting the die block in the machine, and a washer feeding mechanism including washer chutes leading to said passages and registering with said passages when said block is in its operative position.

25. In a machine for embedding washers in rubber heel blanks, the combination of a die block having a number of holes therein corresponding in number and arrangement to the number and arrangement of the washers to be embedded in each blank, plungers movable in said holes for forcing the washers simultaneously into the blanks, means for supporting said die block removably in the machine, washer passages in said block leading from said holes to opposite sides of the block, and two washer feeding mechanisms including washer chutes leading to opposite sides of said block and arranged to register respectively with the washer passages in said die block when the block is in its operative position.

26. In a machine for embedding washers in rubber heel blanks, a die block having a plurality of plunger passages therein, slots leading laterally into said passages from the outer surface of said block, and filler blocks partially closing said slots and cooperating with the walls of said slots to form washer chutes in said die block.

27. In a machine for loading rubber heel blanks with washers, the combination of a plunger for embedding a washer in a rubber heel blank, a support for said blank, a die block in which said plunger is mounted to reciprocate, a washer chute leading downwardly at a sharp angle into the plunger passage, and a gate at the discharge end of said chute controlling the movement of the washers into said passage.

28. In a machine for embedding washers in rubber heel blanks, the combination of a die block having a number of holes therein corresponding in number and arrangement to the number and arrangement of the washers to be embedded in each blank, plungers movable in said holes for forcing the washers simultaneously into the blanks, washer chutes in said die block leading laterally into said holes, washer feeding mechanism including washer conducting tubes supported in the frame of the machine and leading to said washer chutes, and means

for removably supporting said die block in the machine frame and permitting the removal of the die block without disturbing the washer feeding mechanism or said tubes.

29. In a machine for embedding washers in rubber heel blanks, the combination of a die block having a plurality of holes therein, plungers movable in said holes for forcing the washers into the blanks, washer chutes leading into said holes, gates located substantially at the discharge ends of said chutes for controlling the movement of the washers into said holes, mechanism for reciprocating said plungers in said holes, and a lost motion connection between said mechanism and said gates for actuating the gates in timed relationship to the movement of the plungers.

30. In a machine for embedding washers in rubber heel blanks, the combination of a die block having a plurality of holes therein, plungers movable in said holes for forcing the washers into the blanks, washer chutes leading into said holes, a sleeve encircling each of said plungers, a plate secured to the upper ends of said sleeves, a plunger head to which said plungers are secured, a cross head, said plunger head being connected with said cross head to move therewith, means for reciprocating said cross head, and a lost motion connection between said plate and said cross head.

31. In a machine for embedding washers in rubber heel blanks, the combination of a die block having a number of holes therein corresponding in number and arrangement to the number and arrangement of the washers to be embedded in each blank, plungers movable in said holes for forcing the washers simultaneously into the blanks, operating mechanism for said plungers, and a disengageable connection between said plungers and said operating mechanism.

32. In a machine for embedding washers in rubber heel blanks, the combination of a die block having a number of holes therein corresponding in number and arrangement to the number and arrangement of the washers to be embedded in each blank, plungers movable in said holes for forcing the washers simultaneously into the blanks, a plunger head to which said plungers are secured, operating mechanism for said plungers, a slip connection between said head and said mechanism permitting the plungers to be removed laterally from the machine, and means for supporting said die block for removal with said plungers.

33. In a machine for embedding washers in rubber heel blanks, the combination of upper and lower die blocks, means for positioning a heel blank between said blocks, a series of plungers movable in the upper block to press washers flatwise into said blank, said lower die block having apertures

therein to receive stock displaced by said plungers as they embed the washers in the blank, operating mechanism for said plungers, and means whereby the minimum distance between the ends of said plungers and the face of the lower die plate may be adjusted.

34. In a machine for embedding washers in rubber heel blanks, the combination of 10 positioning means for a heel blank, means for feeding a washer on to the surface of a heel positioned by said means, and a plunger for forcing the washer flatwise into the blank.

35. In a machine for embedding washers in rubber heel blanks, the combination of 15 positioning means for a heel blank, mechanism operative automatically to feed a plurality of washers on to the surface of a 20 blank so positioned with the washers arranged in substantially the relationship to the outline of the blank which it is desired to have them bear to the outline of the finished heel, a series of plungers arranged to 25 bear on said washers, and means for operating said plungers to cause them to press said washers simultaneously into the body of the blank.

36. In a machine of the character 30 described, the combination of mechanism for loading a rubber heel blank with washers preparatory to molding and vulcanizing the

blank, and blank feeding mechanism for presenting blanks to said loading mechanism.

37. In a machine of the character described, the combination of mechanism for loading a rubber heel blank with washers preparatory to molding and vulcanizing the blank, means for feeding washers to said 40 loading mechanism, and mechanism for feeding heel blanks to said loading mechanism.

38. In a machine of the character described, the combination of means for embedding a plurality of washers simultaneously in a rubber heel blank preparatory to molding and vulcanizing said blank, and mechanism for presenting blanks successively 45 to said means.

39. In a machine for loading heel blanks 50 with washers preparatory to molding and vulcanizing the blanks, the combination of mechanism for loading a blank with washers arranged in substantially the positional relationship which it is desired to have them bear to each other in the finished heel, and blank feeding mechanism operative to present blanks successively to said loading mechanism in position for said loading operation.

In testimony whereof we have hereunto signed our names to this specification.

VICTOR R. LAWSON.
JOHN J. BATTERMAN.
